UNITED STATES PATENT OFFICE.

CHARLES LE G. FORTESCUE, OF PITTSBURGH, PENNSYLVANIA, ASSIGNOR TO WESTINGHOUSE ELECTRIC AND MANUFACTURING COMPANY, A CORPORATION OF PENNSYLVANIA.

RECTIFIER SYSTEM.

1,130,265.

Specification of Letters Patent.

Patented Mar. 2, 1915.

Application filed June 21, 1912. Serial No. 705,015.

To all whom it may concern:

Be it known that I, CHARLES LE G. FORTESCUE, a subject of the King of Great Britain, and a resident of Pittsburgh, in the county of Allegheny and State of Pennsylvania, have invented a new and useful Improvement in Rectifier Systems, of which the following is a specification.

My invention relates to systems of distribution in which alternating current is rectified by means of mercury vapor and similar devices, and particularly to such systems as embody regulating transformers for maintaining the rectified current substantially constant in value.

The object of my invention is to provide a system of the character indicated, in which means are employed for limiting, to a harmless value, the current that traverses the circuit upon the occurrence of a short circuit in the rectifying apparatus.

My invention is illustrated in the accompanying drawings, Figure 1 of which is a diagrammatic view of a system of distribution embodying the same, and Fig. 2 is a similar view of a modification of the system of Fig. 1.

According to the present invention, two mercury vapor or other suitable rectifying devices 1 and 2 are supplied with substantially constant amounts of current, as shown in Fig. 1, from a single constant-current regulating transformer 3 which comprises a core member 4 having three legs, the central one of which is surrounded by primary coils 5 and 6 and secondary coils 7 and 8. The primary coils 5 and 6 are connected in series or in any other suitable relation, to a supply circuit 11-12. The terminals of secondary coil 7 are respectively connected to the anodes of the rectifier 2, and an intermediate point of the coil is connected to the rectifier cathode, suitable translating devices 13, constituting a load, being included in the latter connection. The secondary coil 8 is similarly connected to the rectifier 1.

In the connections between the secondary coils and the anodes of the rectifiers are included the windings 15, 16, 17 and 18, respectively, of two impedance devices 19 and 20, each of which comprises a magnetizable core 21 having two legs that are respectively surrounded by the said windings, the anodes of each rectifier being respectively connected to windings belonging to different impedance devices.

The cores 21 are preferably provided with air gaps for the purpose of adjusting the reactances afforded by the devices. The coils upon each of the cores are adapted to produce fluxes simultaneously in the same direction; that is, supplementary to each other.

In the operation of the system, the primary coils 5 and 6 are caused, by the magnetic forces acting upon them, to occupy such positions that the current supplied to the rectifiers will be maintained substantially constant, irrespective of the change of load, and, by reason of the peculiar arrangement of the primary and secondary coils with respect to each other, the regulating transformer will also afford sufficient reactance for sustaining the rectified currents. As before stated, the windings of the impedance devices 19 and 20 normally produce supplementary fluxes with the result that normally they introduce comparatively small amounts of reactance into the secondary circuits. The connections are also such that only one of the said devices is active at a time. However, if a short circuit occurs in one of the rectifiers as, for instance, in the rectifier 1, the coils 15 and 17, belonging to different impedance devices, will be simultaneously traversed by current, with the result that the introduction of the additional winding into the circuit traversed by the short circuit current affords sufficient reactance for limiting the short circuit current to a low and harmless value. By reason of the opposition to the flow of short circuit current, the occurrence of the short circuits themselves is rendered difficult and infrequent.

In the system of Fig. 2, two independent regulators are employed instead of one, but otherwise the connections and operation of the system are similar to those of the system of Fig. 1.

I claim as my invention:

1. The combination with transforming apparatus comprising two secondary windings, of two current rectifiers connected to said windings, and two impedance devices each comprising two normally supplementary windings that are respectively interposed in the connections between the rectifiers and the secondary windings of the transforming apparatus.

2. The combination with transforming apparatus comprising two secondary wind-

- ings, of two current rectifiers connected to said windings, and two impedance devices each comprising two normally supplementary windings that are respectively interposed in the connections between the rectifiers and the secondary windings of the transforming apparatus, the connections to each rectifier including a winding of each impedance device.
- 10 3. The combination with transforming apparatus comprising two separate secondary windings, of two current rectifiers connected to said windings, one being connected to one of said windings and the other to the other winding, and two impedance devices

each comprising two normally supplementary windings that are respectively interposed in the connections between the rectifiers and the secondary windings of the transforming apparatus, the connections to each rectifier including a winding of each impedance device.

In testimony whereof, I have hereunto subscribed my name this 18th day of June, 1912.

CHARLES LE G. FORTESCUE.
